CARD ANALYZING MECHANISM FOR
TABULATORS

William Wockenfuss, Union, N. J., assignor to
Control Instrument Company, Inc., Brooklyn,
N. Y., a corporation of New York

Original application March 4, 1948, Serial No.
13,017. Divided and this application July 15,
1949, Serial No. 104,987

3 Claims. (Cl. 235—61.11)

1

This invention relates to improvements in record controlled tabulators and has particular reference to card analyzing means therefor, the present disclosure being a division of my co-pending application Serial No. 13,017, filed March 4, 1948.

An object of the invention is to facilitate access to the interior of the card analyzing mechanism of a tabulator in the event of a card jam so that any mutilated cards therein may be readily and quickly removed, and to also enable repairs and replacements to be made with comparative ease.

Another object is to provide the analyzing section of a statistical card machine with relatively movable frames each of which contains certain operating and control mechanisms that cooperate in the analysis of cards and in the transmission of such analysis to other parts of the machine, and wherein a drive for said mechanisms is mounted in one of said frames for detachable connection to portions of the mechanisms in the other frame to permit of said frames being relatively moved apart to open position.

In carrying out the above objects, the invention provides a construction in which the analyzer section of the tabulator comprises, generally, a main frame carrying portions of the card analyzing mechanism including one of the plates forming a part of a chamber into which cards are fed for analysis, and an auxiliary frame movable to open position relative to the main frame and supporting therein, among other elements, portions of the analyzing mechanism and a second plate which cooperates with the first plate to form said card chamber and which is movable with said auxiliary frame, when the latter is adjusted to open position, to support the two plates of the chamber and thus fully expose for ready access and removal any cards in the analyzing section.

The inventive idea involved is capable of receiving a variety of expressions one of which, for purposes of illustration, is shown in the accompanying drawings; but it is to be expressly understood that said drawings are employed merely to facilitate the description of the invention as a whole and not to define the limits thereof, reference being had to the appended claims for this purpose.

In the drawings:

Fig. 1 is a fragmentary side elevation of the analyzing section of a tabulator constructed in accordance with the invention;

Fig. 2 is a view similar to Fig. 1, partly in section, showing the upper auxiliary frame of the analyzing unit in partially open position; and

2

Fig. 3 is a fragmentary vertical transverse section through the analyzing unit.

The analyzing section comprising the features of this invention includes the front and back plates 31 and 32 and a transverse wall 35 suitably carried upon the base of the tabulator, the wall 35 separating said analyzing section from the remainder of the machine which forms no part of the present invention and by which the analysis of the record cards is transferred to the printing and accumulating mechanisms of the tabulator for the control thereof. Said plates 31, 32 constitute the main frame of the analyzing unit and have pivoted to the upper portions thereof, at 38, 15 the two rails 39 of an auxiliary frame which further comprises the side plates 40 and 41 and a cover plate 42, said pivotal connection permitting said auxiliary frame and the entire mechanism supported thereby to be swung upwardly to a substantially vertical position, after effecting certain disconnections to be later described, in order that ready access may be had to the interior of the analyzing section. The auxiliary frame is held in its horizontal operative position by removable 20 dowel screws 43 extending through the rails 39 and into the side plates 31, 32, and to adequately support said auxiliary frame in its closed position the opposed side rails 39, which are laterally offset relative to the plates 31, 32, carry blocks 25 44 which rest upon the latter plates, as shown in Fig. 3.

Geared, at 54, to a drive means (not shown) is a horizontal shaft 55 (Fig. 3) supported by the rear side plate 32 and having a worm 56 thereon 35 which constantly drives a large gear 57 coupled to one end of the transverse shaft 58 (Fig. 2) having bearings in the plates 31, 32 and operable to control the various functions of the analyzing section of the machine, as fully set forth in the above identified application.

Pairs of upper and lower card feed rollers 11 have their shafts supported in the plates 31, 32, those rollers shown in Fig. 3 being the intermediate pair located vertically between the sensing 45 and analyzing stations generally indicated at 79 and 81 at which cards are compared for group control purposes. The shaft of the lower roller of said pair extends through the front plate 31 and is geared to the horizontal counter shaft 98 45 by a worm 99, and similar pairs of rollers are also geared to the latter shaft and to the shaft 55 on the rear side of the machine so that the various pairs of rollers will operate in unison to feed cards ejected from the magazine 66 carried by 55 the side rails 39 and transmit them to and

through the card chambers 78 and 80 at the stations 79 and 81, after which said cards are deposited by the last set of rollers 77 to the left of Fig. 2 into a stacker chamber (not shown). A picker mechanism of the usual type is utilized to feed cards from the magazine 66 and is operated from the rock shaft 71 connected through the crank 72 to a link 73 actuated by bell crank 74 controlled by a cam (not shown) on the shaft 58.

The two mentioned stations 79, 81 include, respectively, the vertically reciprocating lower pin boxes 103 and 103a that contain the sensing pins 104 by means of which perforations in the cards at said stations are simultaneously sensed while cards are momentarily held in the card chambers by the card stops 82. The two lower pin boxes are of identical construction except that the box 103a contains an additional pin 104 in each row individual to a card column and used for control purposes. Stations 79, 81 further comprise the upper pin boxes 109, 109a supported in position above the pin boxes 103, 103a by attachment to the blocks 44 on the rails 39 so as to be movable with the latter and carry with them the card stops 82 when the auxiliary frame of which said rails form a part is swung to open position. Secured to the pin boxes 109, 109a are the upper plates 78a and 80a which cooperate with the lower plates 78b, 80b to form the card chambers 78, 80, the latter plates being affixed to rails 83 secured to the side plates 31, 32. The upper pin boxes 109, 109a contain, respectively, the rows of pins 110, 111 which are controlled by the sensing pins 104 in the lower pin boxes and when said pins 110, 111 are elevated by said pins 104 passing through perforations in cards being sensed at the two stations, lock plates 114 in the upper pin boxes momentarily hold those pins 110, 111 elevated which have been raised by the pins 104 during the sensing and analyzing operations. The lock plates 114 are under the combined control of reciprocating cross bails 115, only one of which is shown herein. As fully described in said co-pending application, said plates are shifted into locking position relative to elevated pins 110, 111 and remain in such position until the bails are returned to restore said plates and thereby release the elevated pins following the performance of their functions. A rock shaft 119 controls the reciprocation of the bails to shift the lock plates into locking position and said shaft carries a crank 120 to which is detachably connected a link 121 joined to a lever 122 operated by a cam (not shown) on the shaft 58.

The card stops 82 are controlled from a cam on said shaft 58 engaging a lever 125 which is directly in front of the lever 122 and to which is connected a link 126 that is detachably joined to a rock shaft 127 which controls the operation of said stops.

From the construction thus far described, it will now be apparent that when the upper auxiliary frame is swung to open position about its pivots 38, the upper pin boxes 109, 109a and the upper plates 78a and 80a, and other mechanism to be described which is contained in said frame, will be separated from the lower pin boxes 103, 103a and the chamber plates 78b, 80b to thus fully expose the feed rollers 77 and open the card chambers 78, 80 so that mutilated cards may be easily removed in the event of a card jam in the analyzer, or should it be desired to effect repairs to or replacement of parts thus exposed.

Cooperating with the pins 110, 111 in the upper pin boxes is a reciprocating scanning device generally indicated at 211 and whose reciprocation is controlled from the shaft 58 by 5 complementary cams 212 thereon acting upon levers 215, 216 on one side of the machine connected by a cross bar 217, there being a similar arrangement of levers on the opposite side of the machine also controlled by complementary cams 212. The lever 216 on one side of the machine and its equivalent 216a on the other side thereof extend upwardly and are detachably joined to links 220 and 220a connected at 221 to the scanning frame so as to reciprocate the 15 same. The scanning frame, as fully described in said co-pending application, carries sensing pawls 223 which travel over the pins 110, 111 in the two upper pin boxes and are tripped by elevated pins therein to control the movements 20 of slides 225 which, in turn, control the operation of bars 136 forming part of the data transfer mechanism (not shown) located to the left of the wall 35, and also actuate bell cranks 243 forming part of a change of designation control 25 mechanism contained within the upper part of the auxiliary frame between the plates 40, 41; said mechanism further including the setting keys 263 for controlling the type of totals to be taken upon a change of designation.

30 There is also shown one of a number of bars 137 (Fig. 2) which extend through the wall 35 and into the transfer mechanism mentioned above, each of said bars being controlled from an additional control pin in the box 109a that has 35 an extension 113 that trips the lever 145 when said pin is elevated by the previously mentioned additional pin 104 in the lower pin box 103a. All of the levers 145 are carried by a common bail 229 which is rockingly supported on the shaft 230 extending between the rails 39 and said shaft is controlled by a cam on the shaft 58 which operates a bell crank 232. A link 223 detachably connects said bell crank to an arm carried by the rock shaft 230 so as to turn the latter clockwise to operate said bail and thereby cause any lever 145 tripped by a control pin 113 to impart movement to its associated bar 137. This action of the bail takes place before the scanning device 211 starts its movement to the right and the bail is thereafter restored by the spring 235 connected to the bell crank 232.

A panel 300 is attached to the wall 35 and carries the switches and keys employed for accomplishing various controls of the machine.

55 With the parts in the position of Fig. 1, should it be desired to open the analyzing unit, it is only necessary to remove the dowel screws 43 and unlatch the keepers 301 to disconnect the upper ends of the levers and links 121, 126, 216, 216a and 223 from their respective crank arms and links on both sides of the machine, whereupon the entire auxiliary frame and parts supported thereby may be swung upwardly about the pivots 38 to open position.

60 65 What is claimed is:

1. In a tabulating machine, an analyzer section including a main frame, an auxiliary frame for said section movable relative to said main frame from a normally operative position to an open position relative thereto, an operating shaft journaled in said main frame, card analyzing means in said section including a card chamber formed by two opposed plates with one of said plates being carried by said main frame and the other plate being supported by said auxiliary

frame, and said plates being movable relative to each other only when said auxiliary frame is moved to open position relative to the main frame, means carried by said auxiliary frame for transmitting said analyzed data from said analyzing means, an operating connection between said shaft and said transmitting means, and means to disable said connection preliminary to moving said auxiliary frame to open position.

2. In a tabulating machine, an analyzer section including a main frame, an auxiliary frame for said section movable relative to said main frame to an open position, an operating shaft journaled in said main frame, card analyzing means in said section including upper and lower pin boxes, one carried by said main frame and the other by said auxiliary frame, said analyzing means further including opposed plates each carried by one of said pin boxes and being movable relative to each other only when said auxiliary frame is moved to open position relative to the main frame, a reciprocable device for scanning the pins in said other pin box, an operating connection between said shaft and scanning device, and means to disable said connection preliminary to moving 25 said auxiliary frame to open position.

3. In a tabulating machine, an analyzing section

including a main frame, an auxiliary frame for said section movable relative to said main frame to an open position, an operating shaft journaled in said main frame, card analyzing means in said section including upper and lower pin boxes and an intervening card chamber formed by two opposed plates, said lower pin box and one of said plates being carried by said main frame and said upper pin box and the other plate being supported by said auxiliary frame, data transmitting mechanism supported in said auxiliary frame in operative association with said upper pin box, a driving connection to couple said transmitting mechanism and said operating shaft, and means 10 to uncouple said connection to permit movement of said auxiliary frame to open position.
